FIG. 1 is a plan view of the artificial fishing lure design of the present invention with extending appendages positioned as they are when the lure is being drawn steadily through water;

FIG. 2 is a slightly inclined side elevation of the lure of FIG. 1, the other side being identical except for the location of the hook;

FIG. 3 is a front view of the lure of FIG. 1;

FIG. 4 is a view similar to FIG. 2 but showing the extending appendages positioned as they may be during jiggling of the lure in water;

FIG. 5 is a front view of the lure of FIG. 4;

FIG. 6 is a bottom view of the lure of FIG. 4.

I claim:

The ornamental design for an artificial fishing lure, as shown and described.
